GARMENT

Martin Henkin, Brooklyn, N. Y.

Application January 10, 1942, Serial No. 426,342

2 Claims. (Cl. 2—43)

This invention relates to new and useful improvements in ladies' underwear, such as panties, girdles, etc., and it has for its purpose to provide a non-skid underwear or panty with a removable crotch, whereby such underwear may be used with greater convenience and satisfaction than is the case with those now commonly in use, where the said underwear will have a tendency to creep or slide upwards and getting out of position thereby causing great annoyance to the wearer.

With the above and other objects in view, this invention consists of the novel features of construction, combination and arrangement of parts, hereinafter fully described, claimed and illustrated in the accompanying drawing, forming part of this application, and in which similar characters of reference indicate corresponding parts in all views, and in which:

Figure 1 is a plan elevational view of my invention, or ladies' undergarment, as worn by a lady.

Figure 2 is an elevational view of my improved girdle or panty, proper, as the latter will normally appear, when not worn by a person.

Figure 3 is a plan view of the outer side of a detachable crotch piece; while

Figure 4 is a plan view of the inner side thereof.

Figure 5 is a plan view of an undergarment, as described, with parts broken off, and showing the relative connection of the crotch section of the garment, with the crotch piece removed, and the leg straps of the garment, which latter form the essential feature of my invention.

Figure 6 is a bottom view, looking into the leg portion of a girdle, and showing a leg strap on the side of the leg, and also the strip to which a crotch piece is attached.

Referring now more particularly to the drawing, the numeral 10 indicates a lady's girdle or panty, which has the usual upper portion 11 made of knitted elastic material, with accommodation at the bottom thereof to receive the detachable crotch piece 12, secured to the girdle proper in the usual manner, i. e., by means of snap-fasteners, as indicated at 13.

The girdle or panty has, as is generally known, a tendency to slide upward, and to get slightly out of position during the wear by a person, a fact easily observed when noticing how often ladies are exerting a downward pull upon their clothes; this upward movement of the girdle incidentally causes the crotch piece 12 to become wrinkled and to be forcefully drawn upward into

the crotch of the wearer, thereby causing great discomfort to the latter.

In order to remedy this condition, I have devised means in the form of elastic straps 14, which latter will retain the girdle in the proper position, and prevent the crotch piece from being drawn or forced upwardly, or become wrinkled; the said object is further achieved by having the crotch piece extending side-ways inside of the 5 said straps 14, which, as may be noted from Figure 2, form a lateral partial extension to the leg portions 15; the straps 14 are fixedly attached to the latter by seams, as may also be noted in Figure 2. Said straps serve to retain the girdle 10 in the proper position and to prevent the crotch piece from being drawn upwards and become wrinkled, as hereinbefore mentioned.

In further elaborating upon the unique construction of my girdle, it must be noted that the 20 crotch piece 12 is made to extend a considerable distance underneath the side straps 14, that is to about half the width of these, as said crotch piece is secured, for instance, by snap-fasteners, to the strips 16, 16, which latter in turn are fixedly 25 secured to the body portion of the girdle, and also extend, as said before, a distance underneath the straps 14, to about half the width of these, as may be seen in Figure 6, where the line 17 indicates a folding line in the material.

The strips 16 are secured by seams 18 formed by the leg portions 15 and the straps 14, besides being secured at the center to the body portion of the girdle, as shown at 19.

The usual garters 20 are secured to the leg portions, as shown in Figure 6.

It is obvious that slight changes may be made in the form, construction and arrangement of the several parts, as shown, within the scope of the appended claims, without departing from the 30 spirit of my invention, and I do not, therefore, wish to limit myself to the exact construction and arrangement shown and described herein.

What I claim as my invention and desire to secure by Letters Patent of the United States is:

45 1. A garment comprising a form fitting body girdle of elastic material, having at its lower part central dividing lines at the front and back, so as to provide when the material is stretched on a wearer, outer side leg portions, said lines being substantially vertical at their ends on said portions and having medial curved parts just above and around the crotch region, inner side leg extensions, having vertical ends forming permanent junction lines with the vertical lines of the outer leg portions, front and back strips attached to 50 55

said material along said medial parts and extending partly along said vertical junction lines, and a crotch piece of inelastic material, having front and back edges releasably attached to said strips, the ends of said piece being embraced by said inner side leg extensions.

2. A garment comprising a form fitting girdle of elastic material, having at its lower part, back and front central dividing lines, so as to provide when the material is stretched on a user, outer side leg portions, said lines being then substantially vertical at their ends and having medial curved parts just above and around the crotch

region, inner side leg extensions, having vertical ends forming permanent junction lines with said vertical ends on said outer portions, front and back strips attached to said material along said curved parts and partly along said junction lines, fastening elements on each of said strips and a crotch piece of inelastic material, having on opposite side edges thereof fastening elements for releasably cooperating with the first elements, the opposed ends of the crotch piece being free, said free ends being embraced by said inner side extensions against the legs of the user.

MARTIN HENKIN.
